UNITED STATES PATENT OFFICE.

JOSEPH WIESENFELD, OF BALTIMORE, MARYLAND.

CURB ATTACHMENT FOR BRIDLES.

Application filed May 11, 1927. Serial No. 190,468.

This invention relates to a bridle having an improved curb attachment. The bridle has a bit supported from the cheek straps in the usual way, this bit comprising a bar having guards at its ends which extend above and below the bar, and a nose strap is supported independently of the cheek straps, and has secured to its ends chains or bands which cross one another and are attached 10 to the upper ends of the bit guards. A curb rein is attached to the lower ends of the bit guards, and when the curb rein is pulled by the rider, the bit guards, serving as levers, tighten the cross chains under the lower jaw 15 of the horse and draw the nose strap against the horse's nose. The nose strap is provided with rounded nodules which bear at points against the nose of the horse, and the tightening of this strap and the chains causes 20 the horse to release the bit and come under control of the rider.

In the accompanying drawing,

Fig. 1 is a front perspective view of the bridle showing its application to a horse; 25 and,

Fig. 2 is a rear perspective view of the bridle.

Referring to the drawing 1, 2, and 3 indicate, respectively, the crown strap, the 30 brow band, and throat strap of the bridle; and 4 and 5 indicate the cheek straps to which the bit is attached. As shown, the bit comprises a bar 6, having guards 7 and 8 at its ends, these guards extending above 35 and below the bit and having loops 7^a and 8^a, at their upper ends, to which the cheek straps are connected. The driving rein 9 is connected directly to the bit bar, and the curb rein 10 is connected to the lower ends 40 of the guards 7 and 8, as shown.

The nose strap 11 is suspended from the crown strap 1 by straps 12 and 13, the latter having loops through which the ends of the nose strap extend, as shown. One end, 11^a, 45 of the nose strap is connected by a chain 14 to the loop 7^a on the guard 7, at the opposite side of the bit from the end 11^a, and the other end 11^b of said band is connected by

a chain 15 to the loop 8^a on the guard 8. Thus, it will be seen that the ends of the 50 nose band are connected by cross-chains to the guards at the opposite ends of the bit. The nose band is preferably provided with rounded projections 16, adapted to bear 55 against the nose of the horse.

When the bridle is in use, the cross-chains extend back of the lower jaw of the horse, and it will be evident that if the horse becomes fractious and grabs the bit between his teeth, a pull upon the curb rein will cause 60 the bit guards to turn about the axis of the bit, and the upper end portions of said guard will draw the cross-chains tightly around the lower jaw of the horse, and the nose band will be pulled tightly around the 65 nose of the horse and the animal will instinctively release the bit and come under control. It is to be noted that the nose-band is supported independently of the bit, and that the band and the curb chains will 70 not be tightened by pulling upon the driving rein, but only by a pull upon the curb rein.

What I claim is:

1. The combination with a bridle having 75 a crown strap, cheek straps and a bit, the latter comprising a bar having guards at its ends extending above and below the bar, of a nose-band, supported independently of the cheek straps, and curb chains each extending from one end of the nose-band to the upper part of a guard at the opposite side of the bit.

2. The combination with a bridle having 85 a crown strap, cheek straps and a bit, the latter comprising a bar having guards at its ends extending above and below the bar, of a nose-band, straps secured to the crown strap and supporting said band, and curb chains each extending from one end of the nose-band to the upper part of a guard at the opposite side of the bit.

In testimony whereof I hereunto affix my signature.

JOSEPH WIESENFELD.
